UNITED STATES PATENT OFFICE.

HARVEY CONOVER, OF DAYTON, OHIO.

CARTON.

No. 850,345.

Specification of Letters Patent.

Patented April 16, 1907.

Application filed June 8, 1906. Serial No. 320,774.

To all whom it may concern:

Be it known that I, HARVEY CONOVER, a citizen of the United States, residing at Dayton, in the county of Montgomery and State of Ohio, have invented certain new and useful Improvements in Cartons; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in cartons or paper boxes of the type which are especially adapted for dispensing crackers and the like in retail quantities.

The object of the invention is to provide a practically air-tight carton, which, owing to its air-tight features, dispenses with the necessity of inclosing the carton in a separate wrapper.

Preceding a detail description of the invention reference is made to the accompanying drawings, of which—

Figure 1 is a plan view of the blank from which the carton is built. Fig. 2 is a perspective view of the carton folded from the blank, as shown in Fig. 1. Fig. 3 is a sectional view on the line $y-y$ of Fig. 2 with the cover thrown up and a part thereof broken away. Fig. 4 is a section on the line $x-x$ of Fig. 2. Fig. 5 is a section on the line $v-v$ of Fig. 2.

In a detail description of the invention similar reference characters indicate corresponding parts.

The carton is constructed of a suitable quality of cardboard, cut and scored as shown in Fig. 1, where 1 indicates the bottom of the box, united with sides 2 2 and ends 3 3, which are bent upwardly at right angles along the intervening score-lines. (Shown in dotted lines.) The side and end walls 2 and 3 are enabled to be thus bent by intervening triangular folds of the bellows type which fold inwardly along the diagonal score-lines and lie against the inner sides of the end walls 3 3. Extending from the said end walls are flaps 6 6, which fold or bend upon the parallel score-lines and extend down and inclose the bellows folds 4 and 5 against the walls 3 3. The end flaps 6 6 are suitably cut at their ends to provide tongues

7 7, which interlock with the folds 4 and 5 by being projected between them at the diagonal score-lines. (See Fig. 3.) The crackers or other contents of the carton serve to insure this locking engagement between the parts by the pressure exerted thereagainst.

Extending from one of the side walls 2 is a flap 8, which folds inwardly against the inner side of said wall 2 along the intervening score-line. From the other side wall 2 the cover 9 extends and is enabled to cover the mouth of the carton formed by the upright sides 2 and 3 by bending said cover on the intervening score-line separating it from its adjacent side wall 2. The cover 9 has end and side flaps 10 and 11, which bend at right angles to the cover along the intervening score-line and enter the mouth of the vessel or box. The flap 11 engages the flap 8 on the inner side of the latter flap, while the end flaps 10 of the cover lie against the inner sides of the tongues or locking-flaps 6 6. The flaps 8 and 11 are provided with longitudinal beads 12 and 13, which when said flaps are folded inwardly, project inwardly and interlock with each other, one of said beads lying below the other, as shown in Figs. 4 and 5. Owing to the interlocking beads 12 and 13 extending inwardly on the side flaps 8 and 11 and interlocking above and below each other, the said flaps 8 and 11 are enabled to be brought closely together, and the outer sides of the box present a smooth surface. The same is true of the end walls and flaps 3 and 10. In order to bring these interlocking beads 12 and 13 in proper positions to engage each other above and below, the positions of said beads, it will be observed, vary on their respective flaps 8 and 11.

The interlocking bead 13 in the flap 11 being farther away from the adjacent parallel score-line will lie below the bead 12. This interlocking idea is carried out with reference to the end flaps 6 and 10, which have, respectively, beads 14 and 15, which interlock one below the other, as shown in Fig. 4, when the end flaps 10 10 of the cover are projected into the mouth of the box. By means of these inwardly-projecting beads or ribs a substantial lock is effected between the cover and the ends and one side of the box, the other side of the box being joined to the cover 9 in the form of a hinge connection provided by the score-line between said cover and the adjacent side wall 2.

It will be observed from Fig. 2 that the end

and side walls of the carton are devoid of any air-openings and that the only possible space is between the cover and the end and side walls where they come together. These 5 points, owing to the interlocking beads or ribs fitting snugly together, obviate to a very material extent the possibility of air entering at those points. In order, however, to exclude the least possible entrance of air to the 10 interior of the carton at the points just mentioned, a sealing-strip 16 is adhered to the adjacent edges of the cover and side and end walls. This sealing-strip does not interfere with the surface of the cover. Therefore the 15 desired printed matter may be placed upon the cover directly or any portion of the box, thereby dispensing with the application of a printed wrapper to envelop the entire carton.

I claim—

- 20 1. An oblong rectangular box having locking extensions joining the end walls, and a flap extension joining one side wall, a cover extension joining the other side wall, said cover extension having end and side flaps which are adapted to be folded against the locking extensions on the end walls of the box and the flap extension on the side walls of the box, the flap extensions of the cover having inwardly-extended beads which interlock with inwardly-extended beads arranged in a different plane on the locking extensions and the flap extension of the side and end walls of the box.
- 25 2. An oblong rectangular carton, one of the side walls of said carton having an extended flap with an inwardly-projecting bead, the cover of said carton having a similar flap with an inwardly-projecting bead adapted to interlock below the bead on the extended flap of said side wall, the end walls of the carton having extended locking-flaps with inwardly-projecting beads, and the cover of said carton having end flaps with similar beads which interlock below the beads on said locking-flaps.
- 30 3. A four-sided paper box, having a flap extension extending from one of the side walls and lying inwardly against said side wall, said flap extension having a longitudinal rib adjacent to its line of fold, said rib ex-

tending inwardly, a cover extension on the 50 other side wall having a flap extension provided with an inwardly-extended longitudinal rib, said flap extension adapted to lie against the flap extension on the side wall of the box in a position that enables the ribs to 55 interlock one below the other.

4. A four-sided paper box having its cover joined to one of the sides of said box, the other side and the ends of said box having extended flaps adapted to be folded inwardly 60 against the inner side of the ends and sides of the box, said flaps having longitudinal ribs projecting inwardly when the flaps are given their inward folds, the cover of said box having end and side extensions with longitudinal 65 ribs thereon projecting inwardly and adapted to engage below the ribs on the end and side extensions of the box when the cover-flaps are folded inwardly against the end and side flaps of the box.

5. A carton or paper box of oblong rectangular shape having side and end walls joined by triangular folds which lie inwardly when the sides and ends are bent at right angles to the body of the box, a flap extending from 70 each of the end walls of the box with their ends provided with locking-tongues engaging the folds on the inside of the box, said flaps having longitudinal ribs projecting inwardly 75 when the flaps are folded, one of the side 80 walls of the box having an extended flap with a similar longitudinal rib projecting inwardly when the flap is folded inwardly, the other side wall of the box having an extended cover, said cover having end and side extensions or flaps provided with inwardly-projecting longitudinal ribs interlocking below the ribs on the flap extensions on the end and side walls of the box, and a sealing-strip closing the adjacent edges of the extension-flaps 85 on the cover and the body of the box.

In testimony whereof I affix my signature in presence of two witnesses.

HARVEY CONOVER.
